UNITED STATES PATENT OFFICE.

EDWARD M. MOULTON AND MARK MOULTON, OF ROCHESTER, NEW YORK;
SAID MARK MOULTON ASSIGNOR TO SAID EDWARD M. MOULTON.

CLOCK.

SPECIFICATION forming part of Letters Patent No. 408,665, dated August 6, 1889.

Application filed October 4, 1888. Serial No. 287,243. (No model.)

To all whom it may concern:

Be it known that we, EDWARD M. MOULTON and MARK MOULTON, both of Rochester, in the county of Monroe and State of New York, have invented a certain new and useful Improvement in Clocks; and we do hereby declare that the following is a full, clear, and exact description of the same, reference being had to the drawings accompanying this application.

The object of this invention is to so connect the mainspring and mainspring-wheel that said parts may be detached for repairs and applied again without taking the movement apart or disturbing the other gearing. In general principle it is similar to that patented by us September 18, 1888, No. 389,852, a sleeve fitting between the side plates of the frame and an arbor passing through the sleeve being used as in that case.

The special object in this invention is to make a loose connection between the sleeve and arbor; in other words, to avoid the use of screw-threads, which necessitate a number of turns of the arbor in the sleeve to connect the parts immovably together.

To this end the invention consists of a sleeve having its interior square or of equivalent form in cross-section, an arbor of similar form passing loosely through the sleeve, and a suitable fastening device for securing the parts together, all as hereinafter more fully described.

In the drawings, Figure 1 is an edge elevation of a portion of the clock-frame, showing the mainspring, mainspring-wheel, and connecting parts. Fig. 2 is a side elevation looking in the direction of the arrow in Fig. 1. Fig. 3 is an enlarged longitudinal section through the arbor of the mainspring-wheel, showing it also mounted in the clock-frame. Fig. 4 is a perspective view of the sleeve and its tightening-nut, said parts being separated. Fig. 5 is a perspective view of the arbor. Figs. 6 and 7 are cross-sections of the sleeve, showing modifications in the form.

A A indicate the two side plates of the clock-frame, which are of usual form.

B is the mainspring, and C the mainspring-wheel provided with the usual ratchet and

detent. The rest of the gearing is not shown, being of the usual construction.

Our improvement is as follows:

D is a sleeve to which the mainspring-wheel is attached. The sleeve is made of just such length as to fit removably between the side plates A A of the frame. Its interior a is of square form in cross-section. At one end the sleeve is cut with two or more slits b b and provided with a screw-thread c cut on a bevel.

E is the arbor of the mainspring-wheel. It consists of a square body d, two journal-bearings f f, that rest and turn in the side plates of the frame, and a projecting square-sided stem g, that stands outside the frame and forms the winding-stem.

J is a nut that screws on the beveled end of the sleeve D, to clamp the same in place on the arbor, as will presently be described.

m is a hook on the end of the mainspring, which hooks over a pillar K of the frame. Any other suitable device for the purpose may be used, if preferred.

To attach the arbor in place, the sleeve D is first slipped up into position between the sides A A of the frame. This is readily done, as the sleeve is of such length as to fit easily between the said sides. The arbor is then inserted endwise through the sleeve, the body d resting in the interior a of the sleeve, the journals f f resting in the sides of the frame and the stem g projecting outward beyond the frame. The nut J is then turned up on the beveled thread c on the sleeve, which clamps the end of the sleeve down firmly on the arbor and fastens said parts together. The clamping fastens the parts together, so as to turn as one device. The ends of the sleeve resting against the sides of the frame form stops to prevent end displacement.

The object in this invention is to avoid the cutting of screw-threads shown in our former patent, thus facilitating the insertion and removal of the arbor, lessening the expense and securing perfect protection against turning the arbor the wrong way in cases of mistake in winding.

If desired, the interior of the sleeve and the body of the arbor may be made of other than square form in cross-section. Two such forms

of the sleeve are shown in Figs. 6 and 7, one being triangular and the other elliptical.

If desired to furnish additional security against loose movement, a pin *p* may be used, 5 as shown in Figs. 1 and 3.

Having described our invention, what we claim as new, and desire to secure by Letters Patent, is—

1. In a clock, the combination, with the 10 main wheel and spring, of a sleeve fitting between the sides of the clock-frame and provided with a smooth interior, a winding-arbor fitting loosely in said sleeve, the ends forming journals resting in the frame and 15 one end projecting, forming a winding-stem, and a fastening device locking said parts together, as shown and described, and for the purpose specified.

2. In a clock, the combination, with the main wheel and spring, of a sleeve fitting between the sides of the clock-frame and provided with a smooth interior, a winding-arbor fitted in said sleeve, the ends forming journals resting in the frame and one end projecting, forming a winding-stem, and a nut screwing on a beveled screw-thread on one end of the sleeve to clamp the sleeve and arbor together, as herein shown and described. 20 25

In witness whereof we have hereunto signed our names in the presence of two subscribing 30 witnesses.

EDWARD M. MOULTON.
MARK MOULTON.
